(57) **CLAIM**

The ornamental design for a combined oil drain pan and container, as shown and described.

DESCRIPTION

FIG. 1 is a perspective view of a combined oil drain pan and container, showing a first preferred embodiment of my new design.

FIG. 2 is a sectional view as taken on line 2—2 of FIG. 1, to more clearly show certain ornamental features of the combined oil drain pan and container of FIG. 1.

FIG. 3 is a perspective sectional view similar to FIG. 2, to more clearly show certain ornamental features of the combined oil drain pan and container of FIG. 1.

FIG. 4 is a top plan view of the combined oil drain pan and container of FIG. 1.

FIG. 5 is a front elevation view of the combined oil drain pan and container of FIG. 1, the rear elevation being substantially identical thereto.

FIG. 6 is a bottom plan view of the combined oil drain pan and container of FIG. 1.

FIG. 7 is a first end elevation view of the combined oil drain pan and container of FIG. 1; and,

FIG. 8 is a second end elevation view of the combined oil drain pan and container of FIG. 1.
